UNITED STATES PATENT OFFICE.

LOUIS SCHUTTE, OF PHILADELPHIA, PENNSYLVANIA.

STEAM-JET EJECTOR.

SPECIFICATION forming part of Letters Patent No. 295,293, dated March 18, 1884.

Application filed February 21, 1883. (No model.)

To all whom it may concern:

Be it known that I, LOUIS SCHUTTE, of Philadelphia, in the county of Philadelphia, in the State of Pennsylvania, United States of America, have invented certain new and useful Improvements in Jet-Ejectors, of which the following is a specification.

The present invention consists in the peculiar construction and relative arrangement of the several parts of a steam-ejector for the purpose of producing an apparatus of the smallest possible size in cross-section.

Referring to the accompanying drawings, Figure 1 represents a vertical central cross-section of my apparatus. Fig. 2 is a side elevation of the same. Fig. 3 is a cross-section on the line *xx* of Fig. 1.

In proceeding to construct my apparatus I first cast complete in one piece a body, *I*, of the form represented in the drawings, with two flattened sides and a semicircular lower end. Within this body there is formed a reversible opening or passage, *G*, which communicates at its upper end near one side of the body with a tubular neck or throat, which is threaded externally to receive the coupling for connecting the steam-pipe *D* therewith. At its opposite and inner end the passage *G* terminates in a steam-nozzle, *A*, the mouth of which is extended in an upward direction. At its lower end the body has formed upon it a tubular central neck, which is threaded internally to receive and suspend the suction-pipe *F*, through which the water or other fluid to be elevated may be drawn into the apparatus. Into the top of the body, directly over the nozzle *A*, I screw the combining-tube *C*, the lower end of which is expanded to encircle the steam-nozzle *A*, and the upper end of which is made of increasing diameter toward its delivery end.

It will be observed that the tube *C* is provided with an external thread and screwed into place in the top of the body *I*, this construction permitting the tube to be readily re-

moved in order to give access to the interior 45 of the apparatus in the event of its becoming necessary.

To the upper end of the mixing-tube *C*, I connect, by a suitable coupling-joint, the vertical delivery-pipe *E*.

It will be observed that the steam-pipe *D* and delivery-pipe *E* stand in a vertical position, and that they connect with the top of the body near opposite sides thereof, so that they serve jointly to sustain the weight of the body 55 and of the pendent suction-pipe *F*. This arrangement admits of the weight being distributed between the two upper pipes, and also disposes of the weight in such manner that the devices have little or no liability to vibrate when in action.

Around the steam-pipe *D*, concentric therewith, I mount a second pipe, *H*, the lower end of which is attached to a coupling to receive the steam-pipe.

An annular air-space is left between the two pipes *D* and *H* for the purpose of preventing the condensation of the steam by the cold fluids in which the apparatus is ordinarily submerged.

I am aware that various ejectors have been constructed with steam and delivery pipes at the top and a suction-pipe at the bottom, and I lay no broad claim thereto.

Having thus described my invention, what I 75 claim is—

In a jet-ejector, the body *I*, having the passage *G* and nozzle *A* therein, combined with the suction-pipe *F*, applied centrally to the lower side, the steam and delivery pipes 80 applied to the top near opposite sides thereof, and the pipe *H*, surrounding the steam-pipe and closed at the lower end, as described.

LOUIS SCHUTTE.
